TRAIN DISPATCHING SYSTEM FOR
RAILROADSNeil D. Preston, Rochester, N. Y., assignor to
General Railway Signal Company, Rochester,
N. Y.

Application May 7, 1929, Serial No. 361,229

36 Claims. (CL. 246—3)

This invention relates to systems for handling railway traffic, commonly known as dispatching or centralized traffic control systems, and more particularly to a communication system for facilitating the transmission of the necessary controls or indications to and from the dispatcher's office or central control point.

In accordance with the present invention, generally speaking, it is proposed to establish communication between the dispatcher's office and each of the several stations along the track one at a time in turn, and transmit from the dispatcher's office to each station as selected the desired controls by impulses in a predetermined code pattern, and simultaneously transmit indications from that station to the dispatcher's office over channel circuits set up sequentially by the same impulses. In transmitting the controls from the dispatcher's office to a station, it is proposed to employ distinctive codes which respectively correspond to the combined operation of the switches and signals at that station required to establish a particular route for train movement, rather than control the switches and signals separately and independently by different codes.

Another characteristic feature of the invention is that it is normally inactive and not operating, but is automatically set into operation upon any change in track circuit occupancy at any station. When thus set into operation, on account of the need for transmitting a new indication to the dispatcher's office of a train movement, the system is organized to scan the whole controlled territory and transmit all of the control codes and indications.

The system, when inactive, may also be set into operation manually by the dispatcher, after he has changed the position of the control levers for some station or stations; and when the system is thus manually set into operation, the stations in turn are quickly selected, starting at the one nearest the dispatcher's office, until the station is reached where a new control is to be transmitted, whereupon the code control and indication channel circuits for that station are automatically set up.

Another feature of the invention is that the dispatcher may, if he wishes, limit the transmission of control codes and the setting up of indication channel circuits to a given station, for as long a time as he wishes, so that he is able to obtain prompt response to lever movements for that station, and prompt information

of change in track circuit occupancy at that station.

Another characteristic feature of the invention is that the operator may at any time manually set the system into operation to obtain a check of the condition of all of the track relays, switch machines, signals, and other controlled devices, and also automatically transmit the necessary control codes to cause the several switches, signals and the like to assume positions corresponding with the then existing positions of the control levers in the dispatcher's office.

Other characteristic features, functions, and advantages of the system of this invention will be in part apparent, and in part specifically pointed out, as the description progresses.

For the purpose of explaining the nature of the invention, and as one specific typical embodiment of the invention, there is shown in the accompanying drawings, in a simplified and diagrammatic manner, the devices and circuits illustrative of the equipment in the dispatcher's office and at way-stations along the track, in the form preferably adopted for controlling traffic on a single track railroad; but it should be understood that the principles and functions of the invention may be employed for the control and indication of switches, signals, or other traffic controlling devices for various other track layouts. To simplify the illustration and facilitate explanation, the parts and circuits are shown in the drawings diagrammatically, with various conventional illustrations, more with the object of making it easy to understand the principles and mode of operation, than with the idea of showing specifically the construction and arrangement of parts preferably employed to fit the practical operating conditions encountered in practice.

In the accompanying drawings, Fig. 1 illustrates the equipment in the dispatcher's office; Fig. 2 the equipment at one station nearest the dispatcher's office; Fig. 3 certain parts and circuits at two other stations, these three figures, when placed end to end, being intended to illustrate the elements or units which are duplicated to make a complete system; and Fig. 4 shows a detail modification of the starting circuits.

In describing in detail the specific embodiment of the invention shown in the drawings, the general organization of the system will be first discussed, and then the operation of the system explained.

The various electrical connections between the

various parts of the equipment in the dispatcher's office and at the several stations are conveniently pointed out in connection with the description of the operation. For simplicity, the circuits have been shown as terminating at (B+), (B-), (+), (-), CN or C, these symbols indicating connections to the terminals of suitable sources of current, such as batteries, motor-generators, or the like. The circuits wholly local to the dispatcher's office or a station are indicated as terminating at (+) or (-). The symbol C indicates a connection to the common wire C; and the symbol CN indicates a connection to a center or mid-tap of the sources indicated by symbols (+) and (-). The symbols (B+) and (B-) indicate connections to the terminals of opposite polarity of a source of current having a center of mid-tap connected to the common wire C, so as to provide energy of opposite polarity for the several line circuits.

The equipment in the dispatcher's office.—At the central control station, conveniently termed the dispatcher's office, where the operator or dispatcher is stationed, the equipment, shown in Fig. 1, comprises in general, a suitable track diagram of the track layout of the territory under the supervision of the dispatcher, with small electric lamps to indicate the presence of trains on various track sections; a number of manually operable levers, two for each station, which the dispatcher manually sets to different positions to control the switches, signals, or the like at the several stations; a plurality of channel circuit selecting means, one for each station, in the form of a group or bank of neutral relays; a power operated rotary circuit controlling device, conveniently termed a station selector, for establishing the necessary electric inter-connections between the banks of channel circuit selecting relays, and the other devices of the dispatcher's office equipment, and also for transferring the communication from station to station; an impulse producing device, one for each station, in the form of a rotary code wheel; and various other manually operable keys for the several stations, relays, and auxiliary circuits for providing the automatic starting and stopping of the system, and its various other functions.

As representative of the track diagram, there is shown in Fig. 1 one end of a passing siding ps, with an OS lamp 6 to indicate, when lighted, that there is a train present on the usual detector track circuit at the corresponding end of the corresponding siding PS in the field. In practice, of course, this track diagram comprises a large number of stretches of track, with passing sidings, cross-overs, and the like, with many indicator lamps, like 6, to show the presence of trains at the various points. Each OS lamp 6 is controlled by an OS relay 7 of the polar type, having a dead-beat armature 8, which is moved to one or the other extreme position, depending upon the polarity of current flowing through the winding of this relay, and which remains in the position in which it was last set, until current of the opposite polarity is supplied to the relay. The OS lamps 6 may be specially controlled, in the manner disclosed in my prior application Ser. No. 199,325, filed June 16, 1927, so that new indications may be readily recognized by the dispatcher.

As representative of the manually operable control levers, there is shown in Fig. 1 a lever SM, preferably arranged to be moved up and down to either of two extreme positions, this

lever being the one used to control the position of the power operated switch at the corresponding end of the siding PS. Another lever SG, movable from an intermediate or middle position (in which it is shown) to the right or left, controls the clearing of the signals at the corresponding end of the distant siding, and selects the direction in which traffic may be permitted to move at that end of the siding. These two levers SM and SG are preferably correlated by position with the track diagram, and may also be identified with the corresponding portion of the track diagram by number, color or the like.

The levers SM and SG are employed to open and close contacts in their different positions. As diagrammatically shown, the lever SM shifts two contact arms or switch members 16 and 17, into engagement with contacts indicated as arrows. Similarly, the lever SG moves a contact arm 18 into three different positions into engagement with contacts indicated as arrows.

The rotary circuit controller or station selector F, in the simplified form diagrammatically shown in Fig. 1, comprises a shaft 20, indicated by dash lines, which is arranged to be driven by a suitable electric motor 21 through a friction clutch 22. It is contemplated that the motor 21 is constantly running and tends to drive the shaft 20, the clutch 22 slipping when the shaft is held stationary. This is merely a typical arrangement, and other devices may be employed for operating the shaft 20.

The rotation of the shaft 20 is controlled step-by-step by a suitable escapement means, which as shown comprises an escapement wheel 23, with a number of teeth around its periphery corresponding with the number of stations of the system. The space between two successive teeth in the escapement wheel 23 represents a movement of the shaft 20 from one station position to the next, and corresponds with one full step of the shaft 20. The escapement wheel is permitted to advance one-half step at a time by a suitable pallet 24 actuated by stepping magnets M and M-1. The shaft 20 rotates clock-wise in the direction indicated by the arrow x.

Fixed to the shaft 20 are eight contact arms 25-32, which are arranged to engage stationary contacts, spaced in a circle around the shaft in the different positions of the shaft. The first few full steps or station selecting positions of these arms are shown in dotted lines. These arms are each connected to wires, the wires being shown as running directly to the arms, but in practice this electric connection would be made through suitable slip rings or the like.

For each station of the system, the equipment in the dispatcher's office comprises a group or bank of channel circuit selecting relays. Such a bank of five relays 1a-5a is shown in Fig. 1 for the first station A nearest the dispatcher's office. A similar bank of relays, not shown, is located in the dispatcher's office for each of the stations of the system.

The channel circuit selecting relays, as 1a-5a, for each station set up channel circuits for the energization of the OS relay 7 and several other indication relays of the same dead-beat polar type, such as 35, 36, 37, and 38, which control the lighting of lamps N and R, associated with the switch machine lever SM to indicate the position of the switch, other lamps E and W, to indicate the direction of traffic set up, either east-bound or west-bound, and a lamp ST, to indicate that the signals are held in the stop

position. The circuits by which these lamps are controlled by the contact fingers 41, 42, 43, and 44 of the respective indication relays 35-38, may be readily traced on the drawings from one terminal of a battery or other suitable source of current indicated by the symbol (+), and the other terminal of that same source, indicated by the symbol (-).

Also associated with each station, in the particular embodiment of the invention shown, is a rotary code wheel CW, which is in the general form of a simple contact drum, arranged to be driven at the proper speed through a suitable friction clutch 45 and small electric motor 46. For simplicity, this drum is shown developed, and comprises five rows of contacts, 47-51, and two continuous contact strips 52 and 53, all suitably secured to the drum of insulating material, and electrically connected together as indicated. As the drum of this code wheel CW rotates, the contacts move from left to right, in the direction indicated by the arrow y, and the contacts in each row engage a stationary contact finger, indicated as an arrow, respectively connected to wires 54-58. The two continuous strips 52 and 53 are respectively connected through brushes or contact fingers and wires 59 and 60 to the positive and negative terminals of the batteries 61, having a midpoint connected to common, these terminals being marked (B+) and (B-). The first contact in each of the rows 47-51, that is, all of the contacts in the right hand vertical column, are connected together and to the strip 52. The second contacts of the rows 35 are connected together and to the other strip 53, and so on, so that contacts in each row are alternately connected to (B+) and (B-). In the row 47 of contacts, the first contact engaged by the cooperating brush connected to wire 58, is longer than the others. In the next row 48, the second contact is longer than the others, in the next row 49 the long contact is the third, and so on, making five code combinations or patterns, each of a long impulse and four short impulses, 45 with the long impulses at a different point in the patterns, as will be obvious.

The code wheel CW is normally held at rest in the position shown by a spring engaged latch or detent 62 engaging a projecting stop 63 on the drum of the code wheel; and this latch 62 is retracted to release the drum and permit it to be rotated by the motor 46, when a code starting magnet CS is energized. Associated with the magnet CS is a relay 64, for the purpose hereinafter explained.

Also associated with each station is a lever relay L, and a manually operable push-button or key SK, having two contact fingers 65 and 66.

The equipment for the dispatcher's office also includes a starting relay G, relays O and P, and a check push-button or key CK.

The system employs four line wires, extending from the dispatcher's office through the territory equipped, which comprise a common wire C, a signal or message line SGL, a stepping line STL, and a station selecting line SS. In the dispatcher's office, the common wire C is connected to the midpoint of the battery 61, and to the circuits at the points designated by the symbol C. The signal line SGL is connected to the contact arm 31 on the shaft 20. The stepping line STL is connected to a line relay LR^a in the dispatcher's office and to the arm 30. This line relay LR^a is of the quick acting polar type, with its armature biased to the neutral position. The station se-

lecting line SS is connected to a slow acting relay O and thence to the arm 25.

Station equipment.—Fig. 2 shows the equipment representative or typical of a station at one end of a passing siding PS, corresponding to the 5 passing siding ps of the track diagram in the dispatcher's office, shown in Fig. 1. Fig. 3 shows certain parts and circuits for two other stations B and C, the parts of the complete station equipment shown at these stations being those relating 10 to station selection.

In the typical example of a station equipment which has been selected to be shown at station A, Fig. 2, it is contemplated that the system will provide for the control of a suitable power operated switch at the end of the passing siding, and the clearing of the four signals 70-73, subject to the control of the usual block signal system, and also for transmitting to the dispatcher's office indications of the occupied or unoccupied 15 condition of the usual detector track circuit at the end of the siding, having a track relay T, and also indications of the positions of the switch, the clearing of the signals, and the direction of traffic set up. 25

For the purpose of indicating the position of the switch, the switch machine SW, connected to and operating the switch points in the usual way, is provided with contact members 74 and 75, operated to an intermediate open position while 30 the switch machine is operating, and to one extreme circuit closing position or the other, when the switch machine has operated the switch points to the corresponding normal or reverse position, and has locked the points. A pair of 35 contact arms 76 and 77 are also operated by the switch machine SW to three different positions, into engagement with contacts shown conventionally, said arms assuming one extreme position or the other when the switch points are over 40 and locked in corresponding position, and assuming the intermediate position while the switch machine is operating.

Associated with each of the four signals 70-73 is a suitable circuit controller, shown conventionally, which is closed when the corresponding signal is cleared. For simplification, two position semaphore signals have been shown, and these signal circuit controllers 78-81 are operated by the semaphores in the usual way. If either 45 of the signals 70 or 71, governing east-bound traffic, is cleared, and its circuit controller 78 or 79 is closed, a circuit is established for energizing a relay ER. Similarly, the clearing of either of the signals 72 or 73 governing west-bound 50 traffic energizes a relay WB. The energizing circuits for these relays may be readily traced on the drawings.

Each station equipment also includes a bank of channel circuit selecting relays 1-5, and a bank 60 of code responsive relays 11-15, five having been shown as suitable for the particular application of the invention assumed. At each station is a line relay LR included in the stepping line STL, and a slow pick-up relay SL, controlled by said 65 line relay. Also, at each station is a station relay S included in the station selecting line circuit SS; and associated with each station relay S are two or more station counting relays a, b, etc., and a slow pick-up relay SP. At the first station 70 A, nearest the dispatcher's office, (see Fig. 2), there are two counting relays a and b, at the next station B, (see Fig. 3), three counting relays a, b, and c, at the next station C, four counting 75 relays, and so on, there being one more

counting relay at each succeeding station than at the next preceding station, in accordance with the distance from the dispatcher's office. The energization of the next to the last counting relay in the series at each station, in the manner hereinafter explained, selects that station and establishes communication between it alone and the dispatcher's office.

Operation

10 The parts are shown in the drawings in the normal or inactive position, with the system not operating, and on the assumption that the switch at station A is in the reverse position, while the 15 four signals 70-73 at that station are all held at stop.

In this inactive condition, the shaft 20 of the station selector F is held stationary by the pallet 24 and escapement wheel 23, the motor 21 being 20 running and the friction clutch 22 slipping. The stepping line STL is de-energized, and the line relay LR^a in the dispatcher's office and the line 25 relays LR at the several stations are all de-energized and their contact fingers are in the neutral or intermediate position. The station selecting line SS is energized from negative (B-) through the back contact 84 of the starting relay G, wire 85, contact arm 25 in the normal position, wire 86, and relay O. The station relays 30 S, which are in series, at all of the stations are likewise energized negatively, moving their contact fingers 87 and 88 to the left, and energizing the relay SP at that station through a circuit 35 readily traced on the drawings through the contact finger 88.

The code wheels CW for all of the stations in the dispatcher's office are held in the initial position by the latches 62, but the motor 46 is running and slipping the clutches 45. The channel selecting relays 1-5^a in the dispatcher's office for 40 station A and for all of the other stations, are all de-energized; and similarly the channel circuit selecting relays 1-5 at station A and at all the other stations are de-energized.

45 At station A, Fig. 2, on the assumption that the signal lever SG for that station was in the middle position shown during the last operation of the system, the code responsive relay 11 is energized, while all of the other relays 12-15 are de-energized. The code responsive relay 11 is thus maintained energized by a stick circuit from (+), through its front contact 100 and its lower winding, and through the back contacts 101, 102, 103, and 104 of the other code responsive relays 12-15. 50 This relay 11, being energized, opens its back contacts 115 and 116, and breaks the clearing circuits for the signals 70-73, so that these signals are held at stop, irrespective of traffic conditions.

60 *Automatic starting.*—The system, when thus at rest, is automatically set into operation by the operation of any track relay. When thus set into operation automatically by a track relay operation, the system automatically sets up all of the channel circuits for all of the stations and 65 transmits all of the code controls. This may be said to be a complete scanning or checking of all the controls and indications.

To explain this operation in detail, for convenience assume that a train enters the detector 70 track circuit at the passing siding PS in Fig. 2, dropping the track relay T, which closes its make-before-break contacts 110 and energizes a repeater relay TR. The relay TR is stuck up through its front contact 111, wire 112, and back contact 113 of the channel circuit selecting relay

5. The relay TR is picked up and stuck up in the same way when the track relay T picks up.

The energization of the relay TR closes its front contact 114 and establishes a starting channel circuit through the lower winding of the starting relay G in the dispatcher's office, which may be traced as follows:—starting at C, front contact 114 of relay TR, wire 115, back contact 116 of relay 1, wire 117, back contact 118 of relay 2, wire 119, back contact 120 of relay 3, wire 121, 10 back contact 122 of relay 4, wire 123, back contact 124 of relay 5, wires 125 and 126, front contact 96 of relay SP, wires 127 and 128, to the signal line SGL, and thence to the dispatcher's office, arm 31, wire 129, lower winding of relay G to (B+). 15

Since the relay SP at each station is energized, there is a similar starting channel circuit for each station, so that if the track relay T at any other station should drop, or pick up, the resultant energization of the relay TR at that station would 20 cause the energization of the starting relay G.

The energization of the starting relay G opens its back contact 84 to de-energize the relay O and the station selecting line SS. This de-energizes the relay S at the several stations, causing 25 their contact fingers 87 and 88 to assume the neutral position. This de-energizes the relay SP at each station. The closing of the front contact 130 of the relay G connects positive (+) to the wire 131, thence over wire 132, contact arm 29, 30 wire 133, back contact 134 of the relay P, wire 135, to the stepping magnet M—I and thence to (—). When the stepping magnet M is de-energized by the dropping of the relay O, the magnet M—I shifts the pallet 24 to permit the shaft 20 to 35 advance one half-step, whereupon (B+) is applied through contact arm 25 (now in the first half-step position) to the station selecting line SS, again energizing the relay O, which in turn energizes the stepping magnet M, and allows the shaft 20 to 40 make another half-step, bringing it into the first full step station selecting position, shown in dotted lines.

During the time required for the slow acting relay O to pick up its armature and cause energization of the stepping magnet M, a positive impulse is maintained on the station selecting line SS, which moves the contact fingers 87 and 88 of the station relay S at each station to the right. This energizes the first counting relay a at each 45 station. At station A, the counting relay a is energized over a circuit from (+), wires 89 and 90, relay a, wire 91, and back contact 92 of the counting relay b to (—). A stick circuit for the counting relay a is established from (+), through 50 its front contact 93, wires 94 and 90, relay a, wire 91, back contact 92 of relay b to (—). At station B, the pick-up and stick circuits for the counting relay a¹ are similar and include a back contact 92¹ of the third counting relay c. At 60 station C, the pick-up and stick circuits for the counting relay a² includes the back contact 92² of the fourth counting relay d; and in the same way, the first counting relay a at each station is picked up by this positive impulse, and is stuck up 65 through the back contact of the last counting relay at that station.

Each station is selected or rendered effective by the closing of front contacts 97, 98, and 99, which are operated by the next to the last counting relay at that station. At station A, these contacts 97, 98, and 99 are operated by the counting relay a, at station B by the counting relay b, and so on. The closing of the front contact 97 completes the energizing circuit for the 75

slow pick-up relay SL at the corresponding station; the closing of the front contact 98 connects positive to upper contact finger of the line relay LR; and the closing of the front contact 99 connects the signal line SCL to the channel circuits at the corresponding station.

Code transmission and channel circuit selection.—With the shaft 20 of the station selector F in the first station selecting position, corresponding to station A, a circuit is established for energizing the code starting magnet CS for that station from (+), through the back contact 136 of the relay P, wire 137, arm 26 (now in its first step position), wires 138 and 139, back contact 140 of the relay 64, wires 141 and 142, magnet CS, wires 143 and 144, relay 64, to (—). The energization of the magnet CS retracts the latch 62 and permits the motor 46 to drive the drum of the code wheel CW at the proper rate. After a time sufficient to release the latch 62, the relay 64 attracts its armature and breaks the energizing circuit for the magnet CS just traced at the back contact 140 of the relay 64, so that the latch 62 is retracted by its spring into position to stop the code wheel CW after one revolution. The relay 64 when once energized, is maintained energized as long as contact arm 26 remains in the first station selecting position by a stick circuit from (—), relay 64, wires 144 and 145, front contact 140 of relay 64, wires 139 and 138, arm 26, wire 137, back contact 136 of relay P to (+). The contact 140 of the relay 64 is preferably make-before-break.

Assuming the levers SM and SG for station A to be in the position shown in Fig. 1, as the code wheel CW rotates, positive and negative impulses are applied to the stepping line STL by the lower row of contacts 41, the first impulse being a long impulse. This circuit for energizing the stepping line STL may be traced from the contacts in the lower row 41, energized with (B+) and (B-) alternately, to the finger engaging this lower row of contacts, wire 58, contact finger 18 of lever SG in the middle position, wire 146, arm 30 in the first station selecting position, wire 147, line relay LR^a to the stepping line STL, and thence through the line relays LR in series for several stations, common wire C, and back to the battery 61.

Thus, the line relay LR^a in the dispatcher's office, and all of the line relays LR, LR¹, etc., at the several stations are energized by alternate (+) and (—) impulses. While the line relays LR at all of the stations are operated, only the one at the first station A is effective to cause any operation, because it is only at this station that the contacts 97 and 98 are closed, these contacts being associated with the station counting relay a at this first station A, but not with the counting relay a at any other station. Similarly, the line relay LR^a in the dispatcher's office, although connected to the banks of channel circuit selecting relays for all of the stations over the bus lines 148 and 149, operates these relays for the first station A only, because the relays for that station 1^a-5^a are the only ones connected through the arm 32 on the shaft 20 to (—).

The operation of the bank of channel circuit selecting relays 1^a-5^a in the dispatcher's office for station A, and the relays 1-5 at station A, in response to the energization of the line relays LR^a and LR by the impulses applied to the stepping line circuit STL, is the same for both banks of relays, and a description of one will serve for

both. Referring to Fig. 2, when the line relay LR is energized with a positive impulse, it moves its contact fingers 150 and 151 to the right, and with a negative impulse to the left. The contact finger 150 is connected to positive (+) over wire 152 and through the front contact 98 of the relay a.

On the first positive impulse on the stepping line STL, current from (+) is supplied, with the contact fingers 150 of the line relay LR to the right, over wires 153 and 154, back contact 254 of relay 2, wires 155 and 156 to the relay 1, thence over wire 157, back contact 158 of relay 2, wires 159 and 160, back contact 161 of relay 3, wires 162 and 163, back contact 164 of relay 4, wires 165 and 166, back contact 167 of relay 5, and thence to (—). This picks up the relay 1, which is at once stuck up through its front contact 162, wires 169 and 156, relay 1 and thence to (—) along the same path above traced.

In the case assumed, the first positive impulse being a long impulse, the contact finger 151 of the line relay LR is held in its right hand position long enough to energize the slow pick-up relay SL over wire 170, relay SL, wire 171, front contact 97 of relay a to CN, indicating the midpoint of a local battery having its positive and negative terminals connected to the contact finger 151.

With the first channel circuit selecting relay 1 at the way station energized by a long impulse, not only is an indication channel circuit set up by the station A in the dispatcher's office, but also a pick-up circuit for the code responsive relay 11 is established. This pick-up circuit for the relay 11 may be traced as follows: commencing at (+), front contact 172 of the relay SL, wires 173, 174, 175, 176, and 177, front contact 178 of relay 1 now closed, wire 179, upper winding of relay 11 to (—). The long impulse, which is positive in the case assumed, is made of sufficient duration to pick up the relay SL and energize a code responsive relay, as relay 11, and permit another code responsive relay to drop and close its back contacts.

The indication channel circuit set up upon the energization of the relays 1 and 1^a, which as shown is used to energize the indication relay 38 may be traced as follows: commencing at C, relay 38 (see Fig. 1), wire 180, front contact 181 of relay 1^a now closed, wire 182, back contact 183 of relay 2^a, wire 184, back contact 185 of relay 3^a, wire 186, back contact 187 of relay 4^a, wire 188, back contact 189 of relay 5^a, wire 190, arm 31 in the first station selecting position, to the signal line SGL, thence to station A (see Fig. 2), then over wires 128, 191, front contact 99 of relay a, wires 192, and 125, back contact 124 of relay 5, wire 123, back contact 122 of relay 4, wire 121, back contact 120 of relay 3, wire 119, back contact 118 of relay 2, wire 117, front contact 116 of relay 1 now closed, wire 193, back contact 194 of relay ER, wire 195, back contact 196 of relay WR, to (—).

The relay 38 being thus negatively energized moves its contact finger 44 to the left to light the lamp ST, indicating that the signals are at stop. If any one of the signals 70-73 should be in a clear position, closing its corresponding circuit controller 78-81, one or the other of the relays ER or WR would be energized, energizing the relay 38 positively and extinguishing the lamp ST.

Upon the next negative impulse applied to the stepping line STL the relays 2^a and 2 are en-

ergized. This negative impulse shifts the contact finger 150 of the line relay LR to the left and applies current from (+), wires 197, 198 and 199 (see Fig. 2), to the front contact 200 of relay 1 now closed, wires 201 and 202, relay 2, wires 203 and 160, and thence through the back contacts of relays 3, 4, and 5 to (-), the same as in the energizing circuit for the relay 1 hereinbefore traced. The relay 2, when energized, is stuck up in the same way as relay 1; and when relay 2 picks up, its back contact 158 breaks both the pick-up and stick circuits for the relay 1, so that this relay is de-energized and remains de-energized.

This energization of the relay 2 closes a second channel circuit for energizing the indication relay 37, which is similar to the channel circuit previously traced, and need not be traced in detail. This second channel circuit is connected to the contact finger 204 of relay ER, the front and back contacts of which are connected respectively to contact fingers 205 and 206 of the relay WR. If one of the east-bound signals 70 or 71 is cleared, the relay ER is energized, closing its front contact 204; and if the west-bound signals 72 and 73 are at stop, the relay WR is de-energized, closing its back contact 205, whereby the indication relay 37 is energized positively to move its finger 43 to the right and light the lamp E. On the other hand, if the west-bound signals are clear, the relay 37 is energized negatively to light the lamp W.

In a similar way, the third impulse, which is positive, energizes the relays 3 and 3^a, establishing a third channel circuit for the indication relay 36. The fourth impulse, which is negative, energizes the relays 4 and 4^a, and establishes a channel circuit for the indication relay 35. Finally, the fifth impulse, which is positive, energizes the relays 5 and 5^a and establishes a channel circuit for the OS relay 7. The last relay 5 or 5^a of these banks of channel circuit selecting relays is not stuck up, but is held up so long as the stepping line STL is energized, the front contact 228 of the preceding relay 4 or 4^a, which is de-energized upon energization of the last relay 5 or 5^a by the opening of its back contact 167, being shunted by the front contact 229 of the last relay 5 or 5^a.

The desired indications are communicated over these channel circuits by energizing the corresponding indication relays positively or negatively. Thus, if the switch is in the reverse position, as shown, the indication relay 36 (Fig. 1) is energized positively through the contact 76 (Fig. 2) to extinguish the light N, while the indication relay 35 is energized negatively, through contact 77, to light the lamp R. While the switch is operating both of the relays 35 and 36 are energized positively to extinguish both lamps R and N; and when the switch is in the normal position, the relay 35 is energized positively to extinguish the lamp R, while the relay 36 is energized negatively to light the lamp N. In a similar way, if the track relay T is energized and its contact finger 207 raised, the OS relay 7 is energized negatively to extinguish the OS lamp 6, while with the track relay T down, the relay 7 is energized positively to light the OS lamp 6.

All of these channel circuits, over which these indications are transmitted, include the front contact 99 of the counting relay *a* at station A, the contact 99¹ of the counting relay *b* at station B, and so on, so that the channel circuits at each station are not connected to the signal line SGL

unless that station is selected by the energization of its corresponding counting relay *a*, *b*, etc. Similarly, in the dispatcher's office the several channel circuits for each station through the bank of channel circuit selecting relays for that station, such as the relays 1-5^a shown for station A in Fig. 1, are connected through the arm 31 of the station selector F to the signal line SGL only when that station is selected. Consequently, the channel circuits for the different stations are isolated both at the stations and in the dispatcher's office; and if any channel circuit connection should happen to be improperly set up, due to the sticking of a relay or the like, the effect of such failure is confined to the particular station affected and does not interfere with the proper transmission of indications over the channel circuits for other stations. This is a desirable feature, characteristic of systems involving station selection, because such channel circuit failures as may occasionally occur are localized and confined to the station affected, and do not cripple the whole system, as may happen in selecting systems of the synchronous type where all of the channel circuits are directly connected to the signal line, so that any channel circuit improperly set up may interfere with all of the other channel circuits.

If the levers SM and SG for station A in the dispatcher's office had been set in some other position at the time of the operation of the code wheel CW and the relays 1-5 and 1-5^a, as just described, the impulses applied to the stepping line STL would be of a different code pattern, and a different one of the code responsive relays 12, 13, 14, or 15 would have been energized, instead of the relay 11, as assumed. During this operation, the indication channel circuits would have been set up in the same way.

The code controls, which may be transmitted by the code wheel CW, depending on the position of levers SM and SG, are selected so that, by a single code transmitted, the necessary operation of the switch and signals for a given train movement may be obtained as effectively as if separate codes for operation of the switch and signals were transmitted. There are four normal train movements to be handled at the end of a passing siding, namely, east-bound traffic straight through (switch normal), or into the siding (switch reverse), and west-bound traffic on the main track (switch normal), or from the siding (switch reverse). According to this invention, a distinctive code for each one of these train movements is transmitted, and in response to that code, the switch machine and signals are controlled in a corresponding way.

As typical of this operation assume that the dispatcher wishes to set the signals and the switch at the passing siding for station A, Fig. 2, for an east-bound train to take the siding. To do this, the dispatcher moves the signal lever SG to the right, assumed to correspond with east-bound traffic, and the switch lever SM to the reverse position shown. This connects the stepping wire STL through arm 30, wire 146, contact finger 18 of the lever SG, wire 208, finger 17 of lever SM to wire 57 cooperating with the group of contacts 48, in which the second negative impulse is the long impulse. Accordingly, when the relay 2 at station A is energized by the second impulse, the relay SL is also energized, the second impulse being a long one, and a pick-up circuit for the code responsive relay 12 is established from positive through the front contact

172 of the relay SL, wires 173, 174, 175, 176, 209, front contact 210 of the relay 2 and wire 211 through the upper winding of the relay 12 to negative. The energization of the relay 12 breaks 5 at its back contact 101 the stick circuit for the relay 11, and as soon as this relay 11 drops, a stick circuit through the lower winding of relay 12 is established through the back contact 212 of relay 11, wire 213, front contact 214 of relay 10 12, wire 215, lower winding of relay 12, wires 216, and thence through the back contacts 102, 103, 104 of the relays 13, 14, 15 to negative (—).

The energization of the relay 12 closes a circuit from (+), through its front contact 217, wires 218, 219 to the switch machine SW, causing it to assume its reverse position, if not already there. Closing the front contact 220 of relay 12 applies current from positive (+) over wires 221 and 222, back contact 116 of relay 11, wire 223, 20 circuit controller 74 in the reverse position, and thence over wire 224 to the signal 71, so that that signal may clear, providing the switch machine 25 is in the corresponding reverse position. In this connection, it should be understood that the control circuits for the signals have been shown running directly to the signals, whereas in practice there would preferably be suitable relays interposed, in the manner shown, for example, in my prior application Ser. No. 199,325, filed June 16, 30 1927.

If the dispatcher wishes to permit an east-bound train to continue on the main track, he would put his signal lever SG in the right-hand 35 position and his switch lever SM in the normal position, opposite to that shown. This would connect the group of contacts 49 to the stepping line STL, so that the third impulse of the series would be the long one, and the code responsive relay 13 would be energized, controlling the 40 switch machine over wires 225 and 226 and front contact 227 of the relay 13, to assume the normal position. This energization of the relay 13 applies current to the wire 223, the same as the 45 energization of the relay 12, but the switch being in the normal position, the circuit controller 74 is in the other position to permit the other signal 70 to clear for the main track.

In a similar way, which need not be described in detail, the dispatcher may set the levers SM 50 and SG for west-bound traffic from the siding, whereupon the group of contacts 55 would be connected to the stepping line circuit STL, making the fourth impulse a long one to establish 55 through the front contact of the relay 4 an energizing circuit for the code responsive relay 14, which would cause the switch machine to assume the reverse position and permit the signal 73 to clear. For west-bound movement on the main track, the row of contacts 56 is used, energizing 60 the code responsive relay 15 to place the switch in the normal position and clear the signal 72.

With respect to the code responsive relays 11-15, it will be noted that each has a stick circuit through its lower winding including a back contact of each of the other relays. Consequently, 65 when any one of these code responsive relays 11-15 is energized through its upper pick-up winding, the stick circuits for all the other relays are broken, and any relay that may have been previously energized is de-energized. In this way 70 the transmission of a new code cancels any condition brought about by the transmission of the previous code, and avoids the necessity of transmitting a cancelling code as well as an operating 75 code for each operation.

Station selection.—After the code wheel CW for station A has completed its revolution and transmitted the five impulses, and after the last relay 5^a has responded, the control is transferred to the next station B.

Referring to Fig. 1, when the relay 5^a is energized, the closing of its front contact 280 establishes a circuit from plus (+) over wire 281, arm 29, of the shaft F in the first station position, wire 133, back contact 134 of relay P, wire 135, 10 stepping magnet M—I to (—). This energization of the stepping magnet M—I advances the shaft 20 one half-step, where the arm 25 engages the contact connected to (B—), thereby energizing the station relays S at all of the stations negatively to cause their contact fingers 87 and 88 to move to the left. This establishes an energizing 15 circuit for the counting relay b at station A over wire 238, front contact 231 of relay a, wires 232 and 233, relay b, to (—). The second counting 20 relay b at each of the other stations is also energized over a similar circuit.

The energization of relay b and the opening of its back contact 92 interrupts both the pick-up and stick circuits for the relay a at the first station A, so that this relay a is de-energized at this station and remains de-energized. The relay a is de-energized in a similar way at all of the other stations upon energization of the relay b. At station A, the relay b is stuck up through the 30 back contact 95 of the relay SP, wire 234, front contact 235 of relay b, wires 236 and 233, relay b and (—). At station B, see Fig. 3, the relay b¹ is stuck up through the back contact 92¹ of the relay c¹. At station C, the relay b² is stuck up 35 through the back contact 92² of the next counting relay d². The same process is continued for the remaining stations, the pick-up and stick circuits for all of the counting relays at each station, except the last one, being taken through the back 40 contact of the last one, and the last counting relay being stuck up through the back contact 95 of the relay SP at that station.

At station B the contacts 97¹, 98¹, and 99¹, determining the effective control of the line relay 45 LR¹ at that station, the operation of the relay SL at that station, and connecting the signal line SGL at that station to the contact finger 124 of the relay 5 at that station, are all associated with the relay b¹, so that when this relay b¹ is energized 50 as just described, station B is then selected.

After the signal selecting line SS has been energized with a negative impulse to select station B, long enough to assure operation of the quick acting counting relays b at the several stations, 55 but not long enough to pick up the slow relay SP, the relay O closes its front contact and energizes the stepping magnet M to advance the shaft 20 another half-step and bring it into the second station B selecting position. In this position, the code wheel CW for station B is operated, and the control codes and indications are transmitted in the same way described for station A.

After the channel circuit selection and code transmission for the second station B has taken 65 place, and the last channel circuit relay for station B, corresponding to the relay 5^a, has operated, the stepping magnet M—I is energized over a circuit through the contact arm 29, which is similar to the circuit including wire 281 and front contact 280 of relay 5^a, whereupon the shaft 20 advances another half-step, and a positive impulse is applied over arm 25 to the station selecting line SS.

This positive impulse does nothing at station A, 75

since the relay *a* can not be picked up, relay *b* is stuck up, and there is no relay *c*; but at station B and the other stations, the counting relay *c* is energized, dropping the counting relays *b* at all stations except station A. The dropping of relay *b* at station B opens contacts 97¹, 98¹, 99¹, disconnecting that station; but at station C the contacts 97², 98² and 99² are associated with the relay *c*, so that communication is now established to station C. After the channel circuits and code controls for station C have been transmitted, the shaft 20 advances another half-step, station selector line SS is again energized with another impulse, this time of the opposite polarity, namely negative, which energizes the next counting relay *d* at station C and the remaining stations; and this same operation is repeated until the shaft 20 has completed a revolution.

The arm 25 on the shaft 20, during the last part of its movement to its initial position, applies a long negative impulse to the station selecting wire SS, which picks up the relays SP at all of the stations and breaks the stick circuit for the last counting relay at that station, whereupon the counting relays at all the stations are de-energized, the starting channel circuits are established, and the system is ready for another operation.

Since the track relays T at the several stations 30 may drop or pick up at various times as trains enter and leave the corresponding track sections, it may happen that a track relay will pick up or drop at a station while the system is operating, but after the corresponding station has been selected and the channel circuits therefor have been set up. It is necessary, therefore, in order that such OS indication may not be skipped, to keep the system in operation, when once started, until all of the new OS indications have been 35 transmitted or cleared out. To accomplish this, provision is made so that whenever the relay TR at any station is energized by dropping or picking up of the corresponding track relay T, it is held up through its stick circuit until the last channel 40 circuit selecting relay, as 5, at that station has been energized to open its back contact 113. At the end of each revolution of the station selector shaft 20, if the relay TR at any station is still 45 energized, due to a change in the track relay at that station which has not been indicated to the dispatcher's office by a previous operation of the channel circuit selecting relays at that station, then the starting relay G is energized in the same 50 way as hereinbefore explained, to assure another revolution of the shaft 20; and this operation continues until all new OS indications have been 55 communicated to the dispatcher's office.

Manual starting.—The system, when inactive, 60 may also be set into operation manually by the dispatcher, either to obtain a check upon the existing conditions, or for the purpose of transmitting a new control. To do this, the dispatcher depresses the checking key CK, which energizes the upper winding of the relay G, directly from 65 (+) over wire 237, relay G, wire 238, arm 32 to (−), and causes the system to carry out the operation of scanning all indications and transmitting all code controls, in the same way as if the system had been set into operation by a 70 track relay T.

The dispatcher may, if he desires, use this 75 checking key CK to start the system into operation, after he has shifted from one or more of the control levers SM or SG to a new operated position; but since in that case, all of the channel

circuits for all of the stations previous to the one for which a new lever movement had been made, would have to be set up, it is proposed to organize the system such that the station selection will take place quickly, without setting up the channel circuits or transmitting the code controls until the station is reached at which a new code control is to be transmitted.

To understand this feature of manual manipulation, assume that the dispatcher puts the 10 levers SM and SG for a given station in a new position and then presses the particular key SK for that station. The closing of the contacts 65 of the key SK picks up the lever relay L, which is stuck up through its front contact 240, wire 15 241, and back contact 280 of the corresponding last channel circuit selecting relay, as 5^a. The closing of the front contact 242 of the relay L applies positive current over wire 243 to a bus 244, which is connected to the relay P. The energization of the bus 244 also energizes the upper winding of the starting relay G over wire 245, checking key CK normal, wire 237, upper winding of the relay G, and to (−) over wire 238 and arm 32.

The station selector shaft 20 is now started in the same way as previously described. Upon reaching the first station selecting position, remembering that the relay P is energized, if the relay L for that station is de-energized, a circuit 30 for energizing the stepping magnet M—I is established from (+) over the back contact 242 of relay L for the station in question, wire 241, contact arm 28, in the position corresponding to that station, wire 248, front contact 134 of relay P, wire 135, magnet M—I to (−). The energization of the magnet M—I advances the shaft 20 one half-step in the same way as previously explained, which in turn results in the energization 40 of the station selecting line SS, and then transfers to the next station. This same operation is repeated until the station is reached at which the relay L is energized.

When the station selector shaft 20 reaches a 45 station selecting position where the relay L is energized, the next energizing circuit for the stepping magnet M—I, through the front contact 134 of the relay P, is open at the back contact 242 of the relay L, so that the shaft 20 is stopped 50 in the selecting position for the station in question. When the relays P and L are both energized, a circuit for energizing the code starting magnet CS is established from (+), through the front contact 136 of relay P, wire 249, arm 27, wire 250, front contact 251 of relay L, wire 139 along the regular energizing circuit for the magnet CS previously traced. This starts the code 55 wheel CW for the station in question and sets up the channel circuits and transmits the new control code in the same way already explained.

When the last relay, as 5^a, for the selected station under consideration is energized, it breaks at its back contact 280 the stick circuit for the relay L, so that this relay is de-energized, assuming that the dispatcher has restored the key SK. When the lever relay L, which is quick acting, is de-energized in this way, an energizing circuit for the stepping magnet M—I is established from (+), through the back contact 242 70 of the lever relay L, wire 247, arm 28, wire 248, front contact 134, of the relay P, wire 135, magnet M—I, to (−). This advances the shaft 20 another half-step, bringing it into position where the station selecting wire SS is energized 75

over arm 25, to bring about selection of the next station.

If the particular lever relay L under consideration is the only one for the several stations which is energized, then upon dropping of this relay L, the bus 244 is no longer energized and the relay P drops, so that, when the shaft 20 has been advanced to select the next station, the stepping magnet M-1 must be energized through the back contact 134 of the relay P, arm 29, wire 281, and the front contact 280 of the last channel circuit selecting relay, as 5a. Consequently, when this next station is selected, the channel circuits therefor are set up, before the next station after that is selected, and the same is true of succeeding stations. In other words, after the channel circuits for the station, at which the lever relay L is energized, have been selected, the system assumes its ordinary or normal condition for scanning all of the channel circuits. The relay P is preferably made slow releasing, so that upon dropping of the lever relay L, the stepping magnet M-1 may be energized to advance the shaft 20, before the relay P opens the energizing circuit for this stepping magnet at the front contact 134.

The dispatcher, however, may set the control levers to different positions for any desired number of stations and operate the key SK at several stations. When this happens, the system passes quickly from station to station, starting with the first station A nearest dispatcher's office, without setting up the channel circuits, until the first station is reached, where the key SK has been depressed, whereupon the channel circuits for that station are set up and the code controls transmitted, after which the relay L for that station is de-energized. Upon de-energization of this relay L, the bus 244 and the relay P are maintained energized by the relay L at the one or more other stations, at which the key SK has been operated, so that the stepping magnet M-1, is at once energized as soon as the shaft 20 advances to each next station selecting position in turn, causing rapid station selection until the next station is reached where the relay L is energized. Upon coming to such station, where the relay L is energized, the channel circuits for that station are set up, and then the system either continues its rapid station selection, or else is restored to its normal condition for scanning all of the channel circuits at the remaining stations, depending upon whether or not there is any other relay L energized.

In this way, the normal operation of setting up all of the channel circuits and transmitting all of the control codes, is rendered ineffective or discontinued, when the dispatcher operates one or more of the keys SK; and when thus manually controlled, the system operates to select the stations quickly, without setting up the channel circuits therefor, except for the station or stations at which the key SK has been operated, whereupon the system is restored to its normal condition for setting up all of the channel circuits and transmitting all of the code controls. If a track relay should drop or pick up at some one or more of the stations, at which the key SK has not been operated, after the revolution of the station selector shaft 20, during which the manual intervention occurred, such change in the condition of these relays causes energization of the starting relay G and assures another revolution of the station selector shaft to clear out the new OS indications. Likewise,

if a key SK is operated, while the system is operating, and the station for that key happens to be one which has already been passed in the process of station selection, the shaft 20 of the station selector F automatically makes another revolution, to transmit the code controls for the station associated with such operated key SK, because at the end of the revolution of the shaft 20 and cycle of station selection, the upper winding of the starting relay G is energized from the bus 244, which remains energized because there is a lever relay L still energized.

If the system is operating at the time the dispatcher depresses the key SK for some one of the stations, the relay P is energized, and the system thereafter transfers quickly from station to station, without setting up the channel circuits for the stations, until the station, corresponding to the key SK which has been operated, has been reached. In other words, whether the system is at rest or is operating at the time the dispatcher actuates a key SK for a given station, communication to that given station is established as quickly as the station selection can be accomplished, the automatic scanning of the indications to be transmitted to the dispatcher's office being for the time being subordinated to the manual control. Putting it another way, the system normally acts, whenever set into operation from the field, to scan all of the indications and transmit code controls to check the existing positions of the various control levers, but the dispatcher may at any time intervene with a manual operation which cuts out this automatic scanning and establishes without delay communication to the station or stations which the dispatcher has selected.

Manually holding a selected station.—In order that the dispatcher may, if he wishes, limit the channel circuit selection to a particular station, provision is made so that, if the dispatcher holds down the key SK for a given station, the code wheel CW for that station continues to rotate, and the bank of channel circuit selecting relays for that station operate repeatedly as long as this key is kept depressed. The closing of the contact 65 of the key SK maintains the relay L energized, independently of its stick circuit, and keeps open at its back contact 242 the circuit through the arm 28 and front contact 134 of the relay P, by which the stepping magnet M-1 is energized. Consequently, as long as the key SK is held down, the shaft 20 of the station selector F is held in the corresponding station selecting position. The closing of the contact 66 of the key SK establishes a shunt over wires 252 and 253 around the back contact 140 of the relay 64, so that the code starting magnet CS is maintained energized, and the code wheel CW continues to revolve as long as the key SK is held down. This continued rotation of the code wheel CW operates repeatedly the banks of channel circuit selecting relay as 1a-5a and 1-5 for the corresponding station.

In this way, the dispatcher may confine communication with any selected station, and will obtain prompt response at that station to the operation of the control levers SM and SG for that station, and likewise prompt transmission of the indications of the condition of the detector track section, position of the switch machine, and indications of the signals.

When the dispatcher releases the key SK, the code wheel CW is stopped by the latch 62 in its initial position, and when the last channel se-

lecting relay, as 5^a has responded the stepping magnet M—1 is energized, and the next station is selected.

While in the illustrative embodiment of the invention shown, a station is assumed to be one end of a passing siding, in many instances in practice it is preferable to organize the system so that both ends of a passing siding or some other zone or portion of the equipped territory, will constitute a station. For example, in making a non-stop meet, the dispatcher should be in communication with both ends of a passing siding so as to be advised promptly when the expected trains arrive at the respective ends of the passing sidings, in order that he can change the position of the switches and indications of the signals promptly to permit the trains to pass each other without stopping. Accordingly, a station in the sense here used, may include a plurality of separated control points along the track, such as the two ends of a passing siding, and in general signifies that particular portion or zone in the control territory with which the dispatcher may elect to hold communication as a whole, for the purpose of obtaining prompt response to lever operations and changes in track circuit occupancy for all points in that zone. In such cases, where the station comprises the two ends of a passing siding or similarly separated control points along the track, a bank of channel circuit selecting relays, such as the relays 1-5, are preferably located at each end of the passing siding, or at the corresponding local control points, so as to avoid long runs of line wire from the various switches, signals, track relays, and the like, to one bank of channel selecting relays at the different points in the zone or territory constituting a station are operated simultaneously, and must have a capacity for all of the channel circuits for that station. A line relay LR is located near each of these banks of channel selecting relays, and also a station relay S and a group of counting relays *a*, *b*, etc., the group of counting relays at each one of these points being the same, so that the line relays at these points are simultaneously effective to operate the banks of channel circuit selecting relays at these points. The bank of channel circuit selecting relays in the dispatcher's office, such as the relays 1-5, must of course be of a number to take care of all of the channel circuits for the territory or zone constituting the station, and the code wheel CW must be similarly provided with the necessary number of contacts.

In this connection, it will be evident that, by increasing the number of channel circuit selecting relays, such as the relays 1-5, following the same plan of control, and by providing a sufficient number of contacts on the code wheel to operate these relays, any desired number of channel circuits and code controls may be provided for any station. In fact, after an installation has been made, it is easy to add in additional indication or control for any station by merely adding another channel circuit selecting relay and contact on the code wheel for that station. The five channel circuit selecting relays shown are merely typical of what is ordinarily required for one end of a passing siding, but any desired number of relays may be used to fit any number of switches, signals, track relays, and the like, for any desired zone or territory.

In the arrangement hereinbefore described, since it may take several seconds for the switch

machine to respond to a new control, the indication of the changed position of the switch may not be transmitted until some revolution of the station selector F subsequent to the revolution during which the control for the switch was transmitted. The dispatcher may hold down the key SK for a given station, until the indication of the response of the switch or signals to a new control has been received, or may keep the system in operation by the key CK, until the desired indications have been received. To avoid the need for such manual manipulation on the part of the dispatcher, I preferably employ the arrangement of circuits for controlling the starting of the system shown in Fig. 4, which to 15 avoid confusion has not been shown in Fig. 2.

Referring to Fig. 4, the relays ER and WR, responding to the changes in the indications of the signals 70—73 are provided with suitable make-before-break contacts 262 and 263, which are momentarily closed when these relays are energized or de-energized. A contact 264, operated by the switch machine, reverses the polarity of the energizing current for a neutral relay 265, after the switch is operated to its extreme positions; and this relay 265 operates similar make-before-break contacts 266, the armature of this relay momentarily dropping during the reversal of the polarity of the current flowing in its windings. These contacts 262, 263 and 266 are connected in multiple with the contact 110, operated by the track relay T, to close an energizing circuit for a relay X, so that this relay X is energized whenever there is a change in the operated condition of the track circuit, the switch, or the signals. The relay X has a stick circuit including its front contact 267, wire 268, and back contact 269 of the relay SP shown in Fig. 1. The closing of the front contact 270 of the relay X energizes the relay TR, shown in Fig. 2, which is stuck up in the same way through back contact 113 of the relay 5.

With this arrangement, whenever there is a change in the operated condition of the track relays, switch machine, or signals, the relay X is energized, and in turn the relay TR, establishing the same starting circuit hereinbefore explained. If this change takes place while the system is inactive in its initial condition, the relay SP being energized, the relay X picks up and drops while the relay TR is held energized until the bank of relays 1-5 for the station in question has been operated. Since this change in the operated condition of the track relay, switch machine, or signals, may take place while the system is operating, and at any time in its cycle of operation, and perhaps after the channel circuit selecting relays 1, 2, 3, or 4 have operated, but prior to the operation of the relay 5, the relay X and its stick circuit are provided, so as to insure at least one complete cycle of operation following energization of the relay X. If the relay X is energized, while the system is operating it is maintained energized, by its stick circuit, the relay SP being then de-energized. An operation of the relay 5 during this cycle does not de-energize the relay TR, which is held up by its pick-up circuit through the front contact 270 of the relay X. After the cycle of operation under consideration has been completed, and the relay SP is energized, the relay X drops, setting up conditions for the relay TR to drop upon the next operation of the channel circuit selecting relay 5.

In this way, one complete cycle of operation of the system is assured following any change in the

operated condition of the track relay, switch machine, or signals, at any one of the several stations. Consequently, even though the system should automatically stop after the transmission of a control to operate switch or signals at some station, it is automatically started again, as soon as the switch or signal has responded, so as to transmit the indication of the changed condition. Also, if the switch machine or signals at any of the stations is for any reason operated or displaced from the position it last assumed in response to a control by the dispatcher, the system is automatically set into operation and indication of such change is at once communicated to the dispatcher.

From the foregoing it can be seen that this invention provides a communication system for train dispatching or centralized traffic control systems, in which positive acting simple relays are employed for the channel circuit selecting means and code responsive means. These relays can be installed in ordinary relay boxes along the track, and will operate more reliably under the varying conditions of moisture, temperature, and jar and vibration of passing trains, than mechanical selecting devices.

Since the communication between the dispatcher's office and the several stations is established only one station at a time, the channel circuit selecting means and code responsive means at each station are operated only one at a time, and may be the same at the several stations. In other words, a bank of five channel circuit selecting relays and five distinctive code patterns may be employed without interference at several stations, in marked contrast to a system in which the channel circuit selecting or code responsive devices operate simultaneously at all of the stations, so that the equipment at each station must have the capacity to set up channel circuits distinctive from all other stations and respond to codes distinctive from all other stations.

By employing one long impulse in the series or group of impulses which operate the channel circuit selecting relays, it is possible to obtain distinctive code patterns of impulses, as many in number as the total channel circuit selecting relays, with the result that there is great economy in apparatus and in time of operation, because a number of controls may be transmitted from the dispatcher's office and a number of indications received in the dispatcher's office simultaneously with an equal number of channel circuit selecting relays. For example, if five channel circuit selecting relays are used, as shown, five distinctive controls may be transmitted from the dispatcher's office and simultaneously five distinctive channel circuits are set up over which an equal, or greater number, of indications may be received. In other words, the channel circuit selecting equipment is made to do double duty.

While various schemes of station selection may be employed, such as disclosed, for example, in my prior application, Ser. No. 348,336, filed March 19, 1929, in the particular scheme herein disclosed, the station selection is accomplished in a simple and reliable way by the sequential operation of neutral counting relays *a*, *b*, etc.; and in this connection, instead of using as many counting relays at each station as there are stations, by provision of the slow pick-up relay *SP*, energized by a long impulse of one polarity at the end of each cycle of station selection, only two counting relays are required at the first station, three at the next, four at the next, and so on. Also, the use of the

slow pick-up relay *SP* and the long impulse at the end of the cycle of station selection provides for automatic synchronization of the station selecting devices, so that any occasional improper operation of the counting relays is automatically corrected, since the long impulse at the end of the cycle of station selection, by energizing the relay *SP*, de-energizes all of the counting relays *a*, *b*, etc., at all of the stations, and assures that they will start off together on the next cycle of station selection.

Another desirable feature of the invention is that the dispatcher may manually select any station or stations without delay, and may promptly transmit a control to, or receive an indication from, such selected station or stations. Also, the dispatcher may confine communication to any selected station for any desired length of time, so that response to lever movements for that station or transmission of OS indications from that station, are not delayed by the setting up of channel circuits or transmission of code controls to the other stations. Consequently, the dispatcher is able from time to time to place himself in practically direct communication with any selected station at any time, as he finds necessary. Under operating conditions ordinarily encountered, the dispatcher can foretell from the position of trains and their running times the siding or other point in his territory where the arrival or departure of trains is next likely to require a change in the position of switches or indications of signals. For example, a dispatcher can readily determine ahead of time the siding at which it may be possible to make a non-stop meet, and since he can manually select the station for that siding and confine communication thereto for the time being, he is able to obtain such prompt communication of OS indications and response of the switches or signals to the manipulation of the control levers, that he is able to bring about such a non-stop meet as effectively as if there were direct individual line wire connection between the dispatcher's office and that siding.

In connection with this feature of manual station selection, it will be evident that the dispatcher is out of touch, so to speak, for the time being with the OS indications from stations other than the one he may have selected; and although the system, as disclosed, automatically operates to scan all of the OS indications, as soon as the dispatcher discontinues the individual communication to a selected station, in many instances it is desirable to provide means for storing an indication of the dropping or picking up of the track relays in the manner disclosed in my prior application, Ser. No. 348,336, filed March 19, 1929. This storing feature is not disclosed herein in order to avoid complication.

By employing code responsive relays, such as 11-15, interconnected in the way hereinbefore explained, the transmission of any code control, different from the last one, automatically cancels the condition established by the previous code and sets up in its place a new condition corresponding to the new code. This economizes in apparatus and in time, since it is not necessary to send a code to cancel the existing condition before sending the new code, as in the case in some forms of a selecting system of the code type. Furthermore, rather than control the switches and signals by individual codes, the code controls transmitted correspond to different routes for 75

different train movements, which likewise is a desired economy in apparatus and time.

The particular embodiment of the invention shown is susceptible to considerable modification or adaptation to fit the varying conditions encountered in practice; and it should be understood that the particular organization and structure of devices and circuits specifically shown and described may be modified in many respects, or additional features incorporated, without departing from the invention.

What I claim is:-

1. In a dispatching system, the combination with a dispatcher's office and a station, a stepping line and a signal line extending from the dispatcher's office to the station, selecting means in the dispatcher's office and at the station synchronously operated by impulses on the stepping line and establishing sequentially a plurality of channel circuits including said signal line, and code responsive means at the station governed by the selecting means at said station in accordance with the duration of the respective impulses applied to the stepping line.
2. In a dispatching system, a switch and a plurality of signals at a station, and relays individually controlling both the operation of the switch and the indications of said signals, the energization of any one of said relays automatically de-energizing any of the other relays which may be energized.
3. In a dispatching system of the character described, station equipment comprising, a line relay included in a stepping line circuit and responding to impulses applied thereto, a bank of relays energized sequentially one at a time by the operation of said line relay, a slow acting relay energized when any one of said impulses are maintained longer than a predetermined time interval, and a plurality of relays selectively controlled by the contacts of said bank of relays and said slow acting relay.
4. In a dispatching system, the combination with a dispatcher's office and a way station, a stepping line circuit between the dispatcher's office and said station, a line relay at the station, a bank of relays at the station energized sequentially one at a time by the operation of said line relay, a slow acting relay energized when the stepping line circuit is maintained energized longer than a predetermined interval, a plurality of relays each having an energizing circuit including a front contact of one relay of said bank of relays and a front contact of said slow acting relay, and means in the dispatcher's office for energizing said stepping line circuit with different groups of impulses each having a different one of the impulses in the group of sufficient duration to cause energization of said slow acting relay.
5. In a dispatching system, a dispatcher's office, a plurality of stations, a line circuit, a plurality of impulse counting relays at each station operated over said line circuit sequentially, there being one more counting relay at each station than at the next preceding station, and a slow acting relay controlled over said line circuit for maintaining energized the last counting relay at that station.
6. In a dispatching system, a dispatcher's office, a plurality of stations, a stepping line circuit, a bank of neutral relays at each station energized sequentially one at a time in response to impulses applied to said line circuit, the relays in said banks at the different stations varying in

number, each relay of said bank when energized prevents energization of all preceding relays in that bank, and means for maintaining the last relay of each bank energized while the complete cycle of impulses is being applied to said line circuit. 5

7. In a dispatching system, the combination with channel circuit selecting devices in a dispatcher's office, and at a plurality of way stations, of means for operating said devices by 10 code impulses of different patterns, whereby indications may be transmitted by code synchronously with indications communicated over channel circuits.

8. In a dispatching system, the combination with a dispatcher's office, a plurality of way stations, traffic controlling devices at each of said stations, a stepping circuit and a message circuit connecting said dispatcher's office and the several way stations, indicating means in the dispatcher's office, and means for transmitting over said stepping circuit code combinations of current impulses for governing the traffic controlling devices at said stations one station at a time, and means at said stations for governing the energization of said message circuit for each current impulse applied to said stepping circuit and thereby controlling said indicating means in the dispatcher's office simultaneously with the transmission of controls for governing said traffic controlling devices. 20 30

9. In a dispatching system, a dispatcher's office, a way station, a bank of stepping relays in the dispatcher's office and at said station, a stepping circuit operating the relays in the said banks sequentially and simultaneously, a message circuit, indication means in the dispatcher's office responsive to the energization of said message circuit upon each operation of a stepping relay, means at the station for governing the energization of said message circuit upon each operation of a stepping relay, traffic controlling devices at said station, and control means for said traffic controlling devices at the station selectively responsive to the different combinations of current impulses applied to said stepping circuit for the actuation of said stepping relays, whereby controls may be transmitted from the dispatcher's office to the way station over said stepping circuit simultaneously with the transmission of indications from the way station to the dispatcher's office over said message circuit. 35 40 45 50

10. In a dispatching system, a dispatcher's office, a plurality of stations, a bank of stepping relays at each station, a stepping circuit connecting the dispatcher's office and the several stations, a line relay in said stepping circuit at each station and responding to current impulses applied to said circuit, and means for rendering said banks of stepping relays at the several stations responsive to the corresponding line relay only one station at a time, and means at each station responding to the different code combinations of said impulses applied to said stepping circuit. 55 60

11. In a dispatching system, a dispatcher's office, a plurality of stations, traffic controlling devices at each station, a stepping circuit and a message circuit connecting the dispatcher's office with the several stations, code responsive means at each station controlled entirely over said stepping circuit for governing the traffic controlling devices at that station, and means for transmitting indications from a station to the dispatcher's office over said message circuit simultaneously 70 75

with the transmission of said controls to that station over the stepping circuit.

12. In a dispatching system, a dispatcher's office, a plurality of stations, traffic controlling devices at each station, a stepping circuit and a message circuit connecting the dispatcher's office with the several stations, means for transmitting controls from the dispatcher's office to any selected station over said stepping circuit and for simultaneously transmitting indications from the same station to the dispatcher's office over said message circuit.

13. In a dispatching system, a dispatcher's office, a plurality of stations, traffic controlling devices at each station, a stepping circuit and a message circuit connecting the dispatcher's office with the several stations, manually controllable means in the dispatcher's office for impressing on said stepping circuit any one of a series of current impulses of the same number but having different code characteristics, stepping relays in the dispatcher's office and at each station operated sequentially and simultaneously by any one of said series of impulses, control means at each station responsive to the code characteristics of the impulses of the series then being applied to the stepping circuit, indication relays in the dispatcher's office operatively connected one at a time to said message circuit by said stepping relays, and indication control means at each station for governing the energization of said message circuit for each operation of the stepping relays at that station, whereby controls may be transmitted from the dispatcher's office to a way station simultaneously with the transmission of indications over said message circuit.

14. In a dispatching system for railroads, a dispatcher's office, a station, a stepping circuit connecting the dispatcher's office and said station and including a line wire having a line relay at said office and a line relay at said station in series therein, control levers in the dispatcher's office, means governed by said control levers for impressing on said stepping circuit and line relays any one of a plurality of different code combinations of impulses, step-by-step means in the dispatcher's office and at the station operated synchronously by any one of said code combinations of impulses through the medium of said line relays, traffic controlling devices at the station having different operated conditions governed by said different code combinations of impulses, indication relays in the dispatcher's office, indication control means at the station, a message circuit separate from said line wire and line relays extending from the dispatcher's office to the station, and means including said message circuit and governed by said step-by-step means for actuating said indication relays in accordance with the conditions of the corresponding indication control devices.

15. In a dispatching system for railroads a dispatcher's office, a plurality of stations, a stepping circuit and a message circuit connecting said dispatcher's office and the several stations, a bank of stepping relays in the dispatcher's office and at each station operated synchronously by impulses on said stepping circuit, a plurality of control relays at each station rendered responsive one at a time to the energization of said stepping circuit by the operation of the corresponding bank of stepping relays, indicating means in the dispatcher's office responsive to the energization of said message circuit upon each operation

of a stepping relay, and means at said stations for controlling the energization of said message circuit for each operation of the stepping relays at that station.

16. In a system for governing switches and signals on railroads, a dispatcher's office, a distant way station, step-by-step means in the dispatcher's office and at said station operated synchronously to define a plurality of time-spaced steps, a control line circuit and an indication line circuit connecting the dispatcher's office and said station, means in the dispatcher's office for governing the electrical condition of said control line circuit on the successive steps, and means at the station for simultaneously governing the electrical condition of said indication line circuit on the same successive steps.

17. In a system for governing switches and signals on railroads, a dispatcher's office, a distant way station, a bank of stepping relays in the dispatcher's office and at said station operated synchronously to define a series of steps at predetermined time intervals, a control line circuit and an indication line circuit connecting the dispatcher's office and said station, means at that station responsive to the electrical condition of said control line circuit on successive steps, and means in the dispatcher's office responsive to the electrical condition of said indication line circuit on the same successive steps.

18. In a train dispatching system of the synchronous selector type, a message circuit completed momentarily; a polar indicating relay of the permanent magnet stick type located at the dispatcher's office and included in said circuit; and means at a distant way station for applying potential of one polarity to said circuit when an east bound signal is at proceed, and applying potential of another polarity to said circuit when a west bound signal is at proceed.

19. In a train dispatching system of the synchronous selector type, two message circuits each completed momentarily; two polar indicating relays of the permanent magnet stick type located at the dispatcher's office and each included in one of said circuits; and means at a distant way station for applying potential of one polarity to one of said circuits when an east bound signal is at proceed, applying potential of another polarity to said one circuit when a west bound signal is at proceed, applying current of one polarity to the other of said circuits when either a west bound or an east bound signal is at proceed, and applying current of the reverse polarity to said other circuit when all of said signals are at stop.

20. In a system for governing the positions of track switches and the indications of associated wayside signals located at intervals in an extended territory from a central dispatcher's office, a plurality of station equipments located at intervals in said territory and each including code responsive means for governing the switch and signals adjacent thereto, said station equipments also including indication control devices conditioned in accordance with the position of the corresponding track switch and the indications of the associated signals, control levers and indicating means in the dispatcher's office, and a communication system for establishing communication between the code responsive means of said stations one at a time and the corresponding control levers, said communication system also simultaneously establishing communication between the indication control devices at a station

and the corresponding indicating means in the dispatcher's office.

21. In a dispatching system, a dispatcher's office, a track switch and signals at a distant point, control levers in the dispatcher's office having different positions for the different positions of said switch and the indications of said signals, a stepping circuit extending from the dispatcher's office to said distant point, code creating circuit portions in the dispatcher's office each including in series contacts of said levers and connected to said stepping circuit to conduct to said stepping circuit any one of a plurality of different series of current impulses of the same number but having at least one impulse in each series distinctively different from the corresponding impulse of any other series dependent upon the relative positions of said control levers, and code responsive means at said distant point governed by said series of impulses for controlling said switch and signals.

22. In a centralized traffic control system for railroads, a dispatcher's office, a way station, a track switch and signals at said station controllable to set up different routes for train movements, a stepping circuit, manually controllable means in the dispatcher's office for applying to said stepping circuit different code combinations of impulses one for each route, a plurality of control relays at the way station each being operable to govern both the position of said switch and the indication of said signals to set up a particular one of said routes, and means at the way station for decoding the different code combinations of impulses placed on said stepping circuit, said means energizing one particular control relay only when the corresponding route code combination is decoded.

23. In a dispatching system, a dispatcher's office, a way station, a track switch and signals at said station controllable to set up different routes for train movements, a stepping circuit, manually controllable means in the dispatcher's office for applying to said stepping circuit different code combinations of impulses one for each route and one for all routes at stop, and a plurality of control relays at the station, each being selectively responsive only to a particular one of said code combinations of impulses for governing both the position of said switch and the indications of said signals, whereby any particular route may be set up and whereby all routes may be put to stop.

24. In a dispatching system for railroads, a relay having a control contact operable to at least two positions, a slow acting relay having neutral contacts, a source of energy having positive and negative terminals together with a mid tap, means for connecting one terminal of said slow acting relay to said mid tap of said source, and means including said control contact for connecting the other terminal of said slow acting relay to said positive or negative terminals of said source, whereby the neutral contacts of said slow acting relay remain in retracted positions when said control contact is operated to alternate positions above a predetermined rate, and whereby the neutral contacts of said slow acting relay are actuated to attracted positions when said control contact remains in one of its positions for more than a predetermined time.

25. In a dispatching system for railroads, a dispatcher's office; a plurality of way stations; a line circuit connecting the dispatcher's office with the way stations; means in the dispatcher's office for energizing said line circuit with impulses above a

predetermined rate and for prolonging selected impulses; a line relay at each way station included in said line circuit and having a control contact operable to at least two positions; a slow acting relay at each way station, said slow acting relays having neutral contacts; a source of energy at each way station having positive and negative terminals together with a mid tap; means at each way station selectively connecting one terminal of its respective slow acting relay to the mid tap of its respective source; and means including said control contact at each station for connecting the other terminal of said slow acting relay at that station to said positive or negative terminals of its respective source; whereby the neutral contacts of said slow acting relays remain in retracted positions when said control contacts are operated to alternate positions above a predetermined rate; and whereby the neutral contacts of said slow acting relays are actuated to attracted positions when said control contacts remain in one or the other of their positions for more than a predetermined time.

26. In a dispatching system for railroads, a dispatcher's office; a plurality of way stations; a line circuit connecting the dispatcher's office with the way stations; means in the dispatcher's office for energizing said line circuit with impulses above a predetermined rate and for prolonging selected impulses; a line relay at each way station included in said line circuit and having control contacts operable to at least two positions; a slow acting relay at each way station, said slow acting relays having neutral contacts; a source of energy at each way station having positive and negative terminals together with a mid tap; station selecting means at each station for rendering said slow acting relays at the several stations responsive to their respective control contacts at only one station at a time; and means including said control contact at each station for connecting the other terminal of said slow acting relay at that station to said positive or negative terminals of its respective source; whereby the neutral contacts of said slow acting relays remain in retracted positions when said control contacts are operated to alternate positions above a predetermined rate; and whereby the neutral contacts of said slow acting relays are actuated to attracted positions when said control contacts remain in one or the other of their positions for more than a predetermined time.

27. In a dispatching system, a dispatcher's office, a track switch and signals at a distant point, control levers in the dispatcher's office having different positions for the different positions of said switch and the indications of said signals, a stepping circuit extending from the dispatcher's office to said distant point, code creating circuit branches in the dispatcher's office including in series contacts of said control levers for impressing on said stepping circuit any one of a plurality of different series of current impulses each of said series being determined in accordance with the relative positions of said control levers, a control relay at said distant point for each different series, each control relay corresponding to a route over said track switch, and means governed by each control relay for clearing the one of said signals corresponding to the route to which that control relay is assigned, only when said track switch is aligned for the corresponding route.

28. In a dispatching system, a dispatcher's office; a track switch and signals at a distant

point; control levers in the dispatcher's office having different positions for the different positions of said switch and the indications of said signals; a stepping circuit extending from the dispatcher's office to said distant point; code creating branches in the dispatcher's office each including in series contacts of said control levers for impressing on said stepping circuit any one of a plurality of different series of current impulses, each of said series being determined in accordance with the relative positions of said control levers; a control relay at said distant point for each different series of current impulses, each control relay corresponding to a route over said track switch; and means governed by each control relay for aligning said track switch for the corresponding route and for clearing the corresponding signal governing traffic thereover, whereby a route can not be cleared until said track switch has been governed.

29. In a centralized traffic control system for railroads, a control office, a field station, traffic controlling devices at said field station, a stepping circuit connecting the control office and said field station, a plurality of manually operable control levers in said control office each of said levers being capable of assuming a plurality of positions, code transmitting circuit branches in the control office each including contacts of said control levers in series and capable of integrating the positions of said plurality of control levers for impressing on said stepping circuit composite codes characterizing such integrated lever positions, and code receiving means at the field station capable of differentiating said composite codes for controlling the plurality of traffic controlling devices to positions corresponding to their respective levers.

30. In a centralized traffic control system for railroads, a control office, a field station, a railroad track switch at said field station, a switch machine for operating said track switch, signals for governing traffic over said track switch, a stepping circuit connecting the control office and the field station, a switch machine control lever in the control office capable of assuming either of two positions, a signal control lever in the control office capable of assuming either of three positions, code transmitting circuit branches in the control office each including contacts of said control levers in series and capable of integrating the positions of said switch machine control lever and said signal control lever for impressing on said stepping circuit composite codes representative of particular routes over said track switch said codes comprising a predetermined number of impulses, and code receiving means at the field station capable of differentiating said composite codes for controlling said track switch and said signals at that field station, whereby the complete establishment of the route corresponding to the composite route code is accomplished, and whereby failure of establishment of a complete route holds all routes at stop.

31. In a centralized traffic control system for railroads, a control office, a field station, a railroad track switch at said field station, a switch machine for operating said track switch, signals for governing traffic over said track switch, a stepping circuit connecting the control office and the field station, a switch machine control lever in the control office capable of assuming either of two positions, a signal control lever in the control office capable of assuming either of three positions, code transmitting circuit branches in

the control office including contacts of said control levers in series and capable of integrating the positions of said switch machine control lever and said signal control lever for impressing on said stepping circuit composite codes representative of particular routes over said track switch said codes comprising a predetermined number of impulses, and code receiving means at the field station including a route code relay for each of said composite codes, a particular route code relay being picked up only when its corresponding composite code is received, and means controlled by each of said route code relays for operating said track switch and for clearing the particular signal governing traffic over the corresponding route only when said track switch has assumed a proper position for that route.

32. In a dispatching system for railroads, a dispatcher's office, a plurality of stations, a stepping circuit and a message circuit connecting said dispatcher's office and the several stations, a bank of stepping relays at each station operated synchronously by impulses on said stepping circuit, a bank of stepping relays at the office operated synchronously with station banks, a plurality of control relays at each station rendered responsive one at a time to the energization of said stepping circuit by the operation of the corresponding bank of stepping relays, indicating means in the dispatcher's office responsive to the energization of said message circuit upon each operation of a stepping relay, and means at said stations for controlling the energization of said message circuit for each operation of the stepping relays at that station.

33. In a system for governing railway signal apparatus, a central station, a distant field station, a bank of stepping relays in said central station, a bank of stepping relays at said field station, a circuit connecting said stations, means for applying at one station a series of impulses to said circuit to characterize a code, means for causing synchronous step-by-step operation of said banks of stepping relays one step for each impulse of said series impressed on said circuit, code responsive means at the other station distinctively responsive to the code character of said series of impulses, and means including said stepping relay banks and functioning during the transmission of said series of impulses for transmitting an indication from said other to said one station.

34. In a system for governing railway signal apparatus, a central station, a distant field station, a bank of stepping relays in said central station, a bank of stepping relays at said field station, a circuit connecting said stations, means for applying at one station a series of impulses of positive and negative polarity to said circuit said impulses being of long and short duration to characterize a code, means for causing synchronous step-by-step operation of said banks of stepping relays one step for each impulse of said series impressed on said circuit, code responsive means at the other station distinctively responsive to the code character of said series of impulses, and means including said stepping relay banks and functioning during the transmission of said series of impulses for transmitting an indication from said other to said one station.

35. In a system for governing railway signal apparatus and transmitting a return indication, a central station, a distant field station, a bank of stepping relays in said central station, a bank

of stepping relays at said field station, a circuit connecting said stations, means for applying at one station a series of impulses of positive and negative polarity to said circuit said impulses being of long and short duration to characterize a code, means for causing synchronous step-by-step operation of said banks of stepping relays one step for each impulse of said series impressed on said circuit, code responsive means at the other station distinctively responsive to the code character of said series of impulses, and means including said stepping relay banks and functioning during the transmission of said series of impulses for transmitting an indication from said other to said one station in accordance with the polarity of current transmitted during each operation of a stepping relay.

36. In combination, an office and a distant field station, a multiple impulse selector type system for transmitting conditions of traffic from said field station to said office and which is normally at rest, two stick relays for initiating said system the first of which includes a pick-up circuit closed upon a change in traffic conditions and a stick circuit including a contact closed during operation of said system and the second stick relay of which includes a pick-up circuit including a front contact of the first stick relay and a stick circuit including a contact opened when said system has completed its operation, and a contact on said second stick relay for initiating said system.

NEIL D. PRESTON.
